CRANKING TIME LIMITER

Manuel H. Elkin, Elmira Heights, and Frank T. Christian, Elmira, N. Y., assignors to Bendix Aviation Corporation, South Bend, Ind., a corporation of Delaware

Application January 13, 1940, Serial No. 313,764

2 Claims. (Cl. 200—122)

The present invention relates to a cranking time limiter for engine starter controls, and more particularly to a thermostatic controlling device for interrupting cranking after a predetermined time interval.

In certain types of engine installations equipped with automatic starter controls, it is desirable to incorporate in the controlling means a device for interrupting the cranking operation after a predetermined time if the engine fails to start for any reason. This is particularly true in cases where the power plant is normally unattended as in isolated installations for beacon lights and the like, and for certain types of air-conditioning units.

In order to conserve the charge of the starting battery as much as possible, such cranking time limiter should become effective after a time interval sufficient to secure a start under the normal range of operating conditions. Since this normal range may include wide variations in ambient temperatures, battery efficiency, engine stiffness, etc., the time control should be accurate irrespective of such conditions in order to secure consistent operation.

It is an object of the present invention to provide a novel cranking time limiter for internal combustion engines which is accurate and dependable in operation while being simple and economical in construction.

It is another object to provide such a device, the calibration of which is substantially unaffected by usual variations in operating conditions.

It is a further object to provide such a device incorporating a thermostatic controlling device which is positive in action while being susceptible of accurate calibration.

It is another object to provide such a device in which the thermostat operates substantially without sliding friction such as might interfere with the accurate calibration thereof.

It is another object to provide such a device in which the opening and closing of the control contacts by the thermostat take place rapidly and with positive action.

Further objects and advantages will be apparent from the following description taken in connection with the accompanying drawing in which:

Fig. 1 is a semi-diagrammatic representation of an engine starting system incorporating a preferred embodiment of the present invention; and

Fig. 2 is an enlarged detail in perspective show-

ing the thermostatic controlling device with its associated elements.

In Fig. 1 of the drawing there is illustrated a starting circuit for an internal combustion engine, not shown, including a battery 1 connected by a lead 2 to an automatic controlling device indicated generally by numeral 3. This controlling device is of a well-known commercial form including a magnetic switch 4 which is connected by a lead 5 to a starting motor SM, the starting circuit being completed to the battery through the ground.

A control circuit for the magnetic starting switch 4 is provided including a manual switch 6 connected by lead 7 to battery lead 2 and by a lead 8 to a terminal 9 of thermostatic cranking time limiter indicated generally by numeral 11. Terminal 12 of the cranking time limiter 11 is connected to the engine ignition system 20 and also through a lead 13 to a backfire circuit controller 14 which is of a commercial type forming no part of the present invention. The circuit controller is connected by a lead 15 to the solenoid 16 of the magnetic starting switch 4. Solenoid 16 is connected by lead 17 to a contact 18 which is normally in engagement with a contact 19 on a pendulously mounted reed 21 which is grounded at 22 to complete the control circuit.

Means for opening contacts 18, 19 are provided including a coil 23 which actuates a plunger 24 to move a pivoted lever 25 so that its free end engages the free end of the reed 21 and bends it back away from contact 18. Coil 23 is connected at one end by lead 26 to the starting motor lead 5 and is grounded at its other end as indicated at 27. Means for holding contacts 18, 19 open is provided in the form of a coil 28 also grounded at 27 and connected by a lead 29 to a vacuum operated switch 31 mounted on the intake manifold 32 of the engine and having contacts closed by the vacuum in the intake while the engine is running. The switch 31 is connected by lead 33 to terminal 34 of the thermostatic cranking time limiter 11.

As illustrated in Fig. 2, the cranking time limiter comprises a housing 35 having a partition 36 fixed therein dividing it into an upper chamber 37 and a lower chamber 38. A bracket 39 is fixedly mounted on the partition 36, and a bimetallic plate 41 is rigidly fixed thereto at one end as indicated at 42. A bimetallic arm 43 is fixed at one end to the plate 41 as indicated at 44, the two bimetallic parts being thermally insulated from each other as indicated at 55. The plate 41 is arranged so that a rise in

temperature thereof will cause it to bend upward, while the arm 43 is reversely arranged so that when heated it bends downward. A heating coil 46 for the thermostatic arm 43 is grounded at one end thereon as shown at 47 and is connected by a lead 48 to a current regulating device in the form of a ballast tube 49 mounted in the lower chamber 38 of the housing 35. The ballast tube is connected by a lead 51 to terminal 52 of the cranking time limiter which, as shown in Fig. 1, is connected by a lead 53 to the starting motor lead 5.

A flexible yoke member 56 is mounted fixedly on the partition 36 while being insulated therefrom as shown at 57. The yoke 56 is arranged to extend around the thermostatic arm 43, the anchorage 57 for the yoke being located adjacent the bracket 39. The crosspiece 58 of the yoke carries a contact 59 which is normally in engagement with a fixed contact 61 connected by a lead 62 to the terminal 12 of the cranking time limiter. Yoke 56 is connected by a lead 63 to the terminal 9 of the cranking time limiter.

Means for operating the yoke 56 to open contacts 59, 61 by the action of the thermostatic arm 43 is provided in the form of a compression connection between the end of the thermostatic arm and the crosspiece 58 of the yoke. As here shown, this connection is in the form of a compression spring 64, the ends of which are seated in socket members 65 and 66 which are formed to have rocking engagement with the end of the thermostatic arm 43 and the edge of the crosspiece 58 respectively. It will be readily understood that since the spring 64 is under initial compression, it forms in effect a toggle connection with the thermostatic arm 43, and when said arm bends downward beyond the straight-line position, the spring will move the crosspiece 58 upwardly to open contacts 59, 61 with a rapid snap action.

A contact 67 on an insulated bracket 68 is provided to act as a stop for contact 59 and is connected by a lead 70 to a terminal 69 which, as shown in Fig. 1, is connected by a lead 71 to an alarm device 72.

Terminals 9 and 34 are connected by a resistor 73 of suitable value to reduce the current flowing through the coil 28 to a value just sufficient to reliably hold the plunger 24 in its attracted position so as to maintain contacts 18, 19 open.

Means for adjusting the thermostatic arm 43 by flexing the bracket 39 is provided in the form of an adjusting screw 74 tapped into the partition 36. Manual means for returning the yoke 56 to normal position is provided in the form of a plunger 75 slidably mounted in the side of the casing 11 and a bracket 76, and having a conical point 77 adapted to engage the crosspiece 58 to move it to its lower position. A spring 78 is preferably provided for normally maintaining the plunger 75 out of the path of movement of the crosspiece 58.

In operation, closure of the manual switch 6 completes a circuit from the battery 1 through leads 7 and 8 to terminal 9 of the cranking time limiter. Since contacts 59, 61 are normally closed, current flows through lead 63, yoke 56, contacts 59, 61 and lead 62 to terminal 12 from whence it flows through lead 13, circuit controller 14 and lead 15 to the solenoid 16, and from thence through lead 17 and contacts 18, 19 to the ground at 22. Magnetic starting switch 4 is thereby closed, completing the starting circuit from bat-

tery 1 through leads 2 and 5 to the starting motor to initiate the cranking operation. Closure of the starting switch 4 causes energization of the coil 23 of the starter control 3, but attraction of the plunger 24 thereby is resisted by a single turn coil 79 in the cranking circuit which prevents opening of contacts 18 and 19 during the cranking operation. If the engine starts properly, the weakening of the starting circuit by the release 10 of the cranking load from the starting motor permits the coil 23 to overcome the effect of the single turn coil 79, whereupon the plunger 24 is attracted to cause opening of contacts 18, 19, thus breaking the control circuit of the solenoid 15 16 and thereby permitting the starting switch 4 to open. Thereafter contacts 18, 19 are held open by the energization of coil 28 which is energized from the battery through leads 7 and 8, terminal 9, resistor 73, terminal 34, lead 33, vacuum switch 31 and lead 29.

During the cranking operation, closure of starting switch 4 also completes the heating circuit for the thermostatic arm 43, which circuit includes battery lead 2, starting motor lead 5, lead 53, terminal 52, lead 51, ballast tube 49, lead 48, heating coil 46 and ground connection 47. The thermostatic arm 43 is thus caused to be heated during the cranking operation at a rate held substantially constant by the ballast tube 49, and if the engine fails to start after a predetermined time interval, the thermostatic arm 43 bends downward sufficiently to open contacts 59, 61, thus interrupting the control circuit for the magnetic starting switch 4 and causing the cranking operation to cease. At the same time, contacts 59, 61 are closed, completing a circuit through lead 70, terminal 69 and lead 71 to the alarm device 72.

Variations in the operation of the thermostat 40 due to changes in ambient temperatures are prevented by means of the thermostatic plate 41 which serves as a mount for the thermostatic arm 43 and which, as above stated, is reversely arranged in respect thereto. In other words, a 45 rise in ambient temperature which causes the arm 43 to bend downward, will cause the plate 41 to bend upward to a properly corresponding degree. Substantially uniform action of the thermostatic arm 43 is thus secured.

50 When an attendant summoned by the alarm device has removed the inoperative condition of the engine so as to make it possible to start, it is merely necessary for him to actuate the plunger 75 to return the thermostatic contacts 55 to normal position, whereupon the cranking operation will be resumed in the usual manner.

Although but one embodiment of the invention has been shown and described in detail, it will be understood that other embodiments are possible and various changes may be made in the design and arrangement of the parts without departing from the spirit of the invention as defined in the claims appended hereto.

What is claimed is:

65 1. In a cranking time limiter for internal combustion engines, a control circuit including a fixed contact, a flexible U-shaped yoke member anchored at its open end and carrying a contact on its closed end movable by flexure of the yoke 70 member into and out of engagement with the fixed contact, a thermostatic arm anchored at one end adjacent the anchorage of the yoke and extending into the yoke toward its free end, a spring interposed under pressure between the 75 free ends of the arm and yoke to form a snap-

action toggle connection therebetween, means for heating the thermostatic arm at a substantially constant rate during the cranking operation, the consequent flexure of the arm being arranged to open said contacts, and manually operable means engageable with the closed end of the yoke member to close the contacts.

2. In a cranking time limiter for internal combustion engines, a housing, a bracket mounted therein, a thermostatic mounting plate fixed at one end on the bracket, an oppositely arranged thermostatic arm fixed to the other end of the plate and insulated therefrom, a flexible yoke

member anchored to the housing adjacent the bracket in position to surround the thermostatic arm, a compression spring between the end of the arm and the yoke, a fixed contact, a contact 5 on the yoke normally in engagement therewith, means for flexing the bracket to adjust the contacts, and means for heating the thermostatic arm during the cranking operation to cause opening of said contacts after a predetermined time of cranking.
